UNITED STATES PATENT OFFICE

ANNE D. MILLER, OF BRIDGEPORT, CONNECTICUT

DESIGN FOR A SET OF PLAYING CARDS

Application filed February 15, 1932. Serial No. 42,868. Term of patent 14 years.

To all whom it may concern:

Be it known that I, ANNE D. MILLER, a citizen of the United States, residing at Bridgeport, county of Fairfield, State of Connecticut, have invented a new, original, and ornamental Design for a Set of Playing Cards, of which the following is a specification, reference being had to the accompanying drawing, forming part thereof.

The drawing shows the faces of the set of playing cards showing my new design. The dominant feature of the design resides in the pips:

I claim:

The ornamental design for a set of playing cards substantially as shown and described.

ANNE D. MILLER.
